My Knight Mrs
Atts.

United States Patent Office.

WILLIAM S. FREEMAN, OF WEST UNION, OHIO.

Letters Patent No. 80,717, dated August 4, 1868.

IMPROVEMENT IN HAND-LOOMS.

The Schedule referred to in these Letters Patent and making part of the same.

TO WHOM IT MAY CONCERN:

Be it known that I, WILLIAM S. FREEMAN, of West Union, Adams county, Ohio, have invented certain new and useful Improvements in Looms; and I do hereby declare the following to be a full, clear, and exact description thereof, reference being had to the accompanying drawings, making part of this specification.

My improvements have for their object a simple and effective means of opening the "shed" of the warp, and keeping it open for a sufficient period to enable the driving home of the woof-thread by the batten, and an improved arrangement of picker-motion.

In the drawings—

Figure 1 is a perspective view of a loom embodying my improvements.

Figure 2 is a detached view of my picker-staff and treadles combined.

Figure 3 shows my arrangement of treadle-operating arms.

The following parts may be of customary form, and require no specific description, to wit, the frame A, heddles B, treadles C, warp-beam and roller D E, cloth-beam and roller F G, and batten H.

The driving-shaft M is journalled horizontally, transversely of the frame A, at its front end, and is provided at its middle width with a crank, m, of sufficient size to enable the weaver to use both hands when desired, and also, by admitting his body, to enable him to reach any broken thread in the warp, and any other part of the machine or fabric in front of the heddles.

The driving-shaft M carries at its extremities fly-wheels N, connected by pitman O O' to the batten H, and one of them is also connected through its pitman-wrist by a hooped feed-pawl, P, with a ratchet-wheel, Q, upon the shaft R, whose spirally-arranged arms or tappets, S, serve to depress, in appropriate succession, the treadles C. The end of the hook p of the pawl P rests in its backward stroke upon a circular boss, q, on the face of the wheel Q, the wheel meanwhile remaining at rest, so as to prolong the wide-open condition of the shed during the throw of the shuttle, and thus insure the proper stretch and lay of the woof-thread. A pawl, T, engaging in teeth on the rim or periphery of the wheel Q, holds it at rest during the backward stroke of the feed-pawl.

My picker-staff U projects from a shaft, u, journalled vertically in the batten, and to this shaft is attached, by its middle, a strap, V, whose ends are divided and secured to the alternate treadles in the manner shown in fig. 2.

By means of the above-described arrangement of devices, the depression of each respective pair of treadles results in a tension of the respective ends of the strap V, and operates to vibrate the picker-shaft and throw the shuttle.

The cloth-roller G has a ratchet-wheel, g, engaged by a feed-pawl, W, pivoted to a lever, X. A cord, Y, is connected with the lever X, by being passed one or more times around a pin in its side, as shown in fig. 1. One end of said cord being carried backward, is attached to the batten H, and the other, passing over a roller, is provided with a weight, Z, which holds the cord taut under all circumstances, adapting the lever to be oscillated through the cord by the movement of the batten, and thus at each stroke impart a partial revolution to the cloth-roller.

When it is desired to weave the cloth less thickly, it is only necessary to draw the cord slightly through the lever, so as to shorten the distance between the latter and the batten, thus lengthening the stroke of the lever, and consequently increasing the movement which it imparts to the cloth-roller. The cloth then being drawn more rapidly away from the action of the reed upon the woof-thread, the latter is laid up more loosely, and a more open fabric produced.

I claim herein as new, and of my invention—

1. The driving-shaft M, pawl P, ratchet-wheel Q, shaft R, with tappets S, and treadles C, all constructed, arranged, and operating substantially as described, for the purpose set forth.

2. In combination with the elements of claim first, the picker-staff U u and strap V.

In testimony of which invention, I hereunto set my hand.

WILLIAM S. FREEMAN.
